UNITED STATES PATENT OFFICE.

BENJAMIN DENVER COPPAGE, OF WILMINGTON, DELAWARE.

CENTRIFUGAL MACHINE.

1,030,973.

Specification of Letters Patent.

Patented July 2, 1912.

Application filed September 16, 1911. Serial No. 649,604.

To all whom it may concern:

Be it known that I, BENJAMIN DENVER COPPAGE, of Wilmington, Delaware, have invented a new and useful Improvement in 5 Centrifugal Machines, which invention is fully set forth in the following specification.

This invention relates to continuous feed and discharge centrifugal machines or separators of the type illustrated in U. S. Letters Patent of C. S. Lee, 882,256, granted 10 March 17, 1908, wherein the material to be acted upon is continuously fed into one open end of an approximately horizontally disposed rotatable perforated drum, screen or 15 cylinder—rotated at high speed, such as one thousand revolutions per minute, on its approximately horizontal axis —, advanced through said cylinder or rotor at the desired speed, by means such as a fixed spiral conveyor in the rotor, and continuously discharged or delivered from the other open 20 end of the rotor.

While the improvements constituting my present invention have been especially designed 25 for centrifugal machines for removing moisture from coal to dry the same preparatory to coking, and for centrifugal machines for acting upon sugar-cane admixed in a sub-divided state with water for removing 30 from the mixture the water with the sugar dissolved therein, the invention is obviously applicable to centrifugal machines adapted to remove liquid from many other solid materials.

Prominent features of improvement embraced by the invention consist in supporting 35 the rotor by two anti-friction bearings positioned near the middle of the rotor, and applying driving power to the rotor at the 40 middle thereof in symmetrical relationship to and preferably between said two bearings, thereby obtaining an approximate balancing of the rotor, an equal distribution of the strain upon the two bearings and also an 45 efficient and out-of-the-way positioning of the bearings and the driving means; the provision of a heavy annular flange or preferably two such flanges, about the middle of the rotor with the driving means— 50 such for example as a belt—acting upon the rotor between said flanges, the flanges in the rotation of the rotor constituting fly-wheels giving a gyroscopic action tending to resist any tendency of the rotor to wobble 55 or "whip", even at such times as there may be greater weight of material in one end of

the rotor than in the other; and the provision of flanges on the rotor which in rotating at the high speed of the rotor act as centrifugal blowers to create a strong draft 60 in one or more chambers of the casing about the rotor to exit or discharge openings of said chambers, such draft acting to forcibly propel toward the discharge openings of the chambers the liquid extracted by centrifugal 65 action and such solid particles of the material being acted upon as may escape through the perforations of the rotor, thereby preventing such liquid and solid particles from finding their way into the bearings or other 70 parts of the machine from which they should be excluded. These and other structural features embraced by the invention may be more fully understood and readily explained 75 by reference to the accompanying drawings, illustrating several embodiments of the invention, and wherein—

Figure 1 is a longitudinal vertical section, through a machine adapted for example to the drying of coal preparatory to coking; 80 Fig. 2 is a transverse section on line 2—2 of Fig. 1. Fig. 3 is a transverse section on line 3—3 of Fig. 1. Fig. 4 is a longitudinal vertical fragmentary section illustrating a somewhat different form of construction 85 from that shown in the previous figures; Fig. 5 is a transverse section on line 5—5 of Fig. 4. Fig. 6 is a longitudinal vertical fragmentary section of still another form of construction; Fig. 7 is a transverse section 90 on line 7—7 of Fig. 6. Fig. 8 is a longitudinal vertical section, similar to Fig. 1, illustrating a form of construction especially designed for removing liquid from sugar-cane introduced into the machine in a sub-divided condition in admixture with warm 95 water; Figs. 9 and 10 are detail sectional views of the tubular conveyer core and spray nozzles shown in Fig. 8; and Fig. 11 is a diagrammatic view illustrating a series or 100 battery arrangement of three centrifugal machines, such as illustrated in Fig. 8; and Fig. 12 is an end view of the hopper of Fig. 8.

Referring first to the machine illustrated in Figs. 1, 2 and 3, 15 is the main frame or base of the machine resting upon a suitable foundation of concrete or other material. At opposite ends, this base has trough-like inclined walls 16, 17, leading respectively 110 to discharge openings 18 and 19. Secured on this base, as by means of bolts passing

through contacting lips or flanges, Figs. 2 and 3, there are three semi-circular removable caps 20, 21 and 22. The cap 20 is trough-like or V-shape in cross-section, 5 forms a continuation of a similarly shaped portion of the wall of the base 15 and of the trough-like wall 16, these walls of the base together with the cap forming an annular trough-like chamber 13 having the discharge 10 opening 18. The cap 22 is similarly shaped to the cap 20 and with the walls of the base forms an annular trough-like chamber 14 having the discharge opening 19. The semi-circular cap 21 is also secured to the base 15, 15 Fig. 2, showing for this purpose bolts passing through contacting lips or flanges. This cap 21 serves with the main frame particularly to inclose the supporting bearings 20 of the rotor, the heavy flanges or fly-wheels on the rotor, and the driving means for imparting rotation to the rotor.

At the intake or left hand end of the machine, Fig. 1, there is a hopper or chute 23 bolted to the end of the frame 15 and to the 25 cover 20. This hopper secures in place a ring 24 having a flaring annular flange or lip 25 projecting inwardly within ring 62 secured in the end of the rotor and having an inner wall flaring toward the interior of 30 the rotor. A water supply pipe 26 tapped into an opening in the end wall of the hopper 23 serves to deliver into the bottom of the hopper a jet of water having sufficient impacting pressure to dislodge and wash 35 into the rotor particles of heavy material, such as coal, tending to lodge and collect on the bottom of the hopper and under the end of the conveyer core. At the discharge or right hand end of the machine, Fig. 1, 40 there is a downwardly opening discharge hood 27 bolted or otherwise secured to the end face of the base 15 and cover 22.

28 is a single flight fixed spiral conveyer having a core 29, the opposite reduced ends 45 of which are respectively secured in openings in the end walls of the hopper 23 and hood 27. While a single flight conveyer is illustrated, multiple flight or other suitable forms of conveyer for advancing the material through the rotor at the desired speed 50 may be employed.

From the hopper 23 the material is delivered into the open end of a rotatable perforated or foraminated screen, drum or cylinder, which for convenience is herein designated the "rotor." As illustrated in Figs. 55 1 to 3, this rotor is made up of a heavy outer cylindrical shell 30, preferably of brass, and an inner closely fitting lighter cylindrical 60 shell 31 preferably of brass or steel, according to the materials being acted upon. Those portions of the opposite ends of the shell 30 which are surrounded by the annular chambers 13 and 14 are perforated 65 with relatively large openings. Corre-

sponding portions of the walls of the inner shell 31 are also perforated with holes registering with the holes in the outer shell. The holes in the outer shell are preferably larger than those in the inner shell. If relatively fine material is to be operated upon the machine is equipped with an inner shell having small perforations. If coarser material is to be acted upon, the machine is equipped with an inner shell having relatively larger perforations. Furthermore, the perforations 32 at the intake end of the inner shell are preferably made larger than the perforations 33 at the exit end of said shell; at said intake end, the material is in 70 a relatively moist or wet condition and greater opportunity should be offered for the discharge of the liquid by making the openings 32 relatively larger; furthermore, the wet condition of the material, causing 75 small particles thereof to more or less adhere, offers less opportunity for the escape of solid particles through the relatively large openings. At the discharge end of the rotor, there is little liquid remaining to 80 be discharged, the material is relatively dry, and hence the openings 33 should be made relatively smaller to prevent fine solid particles being thrown out through said openings by centrifugal action. 85

Around the middle of the rotor, there is a sleeve or annular band 35 constituting a hub carrying two symmetrically positioned heavy flanges constituting fly-wheels 36, 37, which in rotating with the rotor at high 90 speed produce a gyroscopic action tending to rigidly hold the rotation of the rotor to its normal axis and resist any tendency of the rotor to wobble or "whip", even at such times as there may be greater weight of material in one end of the rotor than in the other. A driving belt 38 passing up from beneath the machine around the hub 35 between the wheels or flanges 36 and 37 serves to drive the rotor, the driving power thus 95 being applied at the middle of the rotor in symmetrical relationship to its ends and to the two supporting bearings about to be described. Suitable driving connections other than a belt may be employed as desired. 100

As illustrated, the rotor is supported in two sets of anti-friction bearings positioned respectively about the rotor at opposite ends of the hub 35. These two sets of bearings, 105 which are similar in construction, each comprise a ring 39 secured on the end of the hub, balls 40 engaging said ring, an outer ring 41 engaging the balls, an annulus 42 bolted to the base 15 and to the cover 20 (or cover 22) and carrying the ring 41; 110 and a ring 43 bolted to the annulus 42. The specific construction of these parts constituting the ball-bearings need not be further described as it forms no part of this invention, and other suitable and efficient forms 115 120 125 130

of anti-friction bearings may be employed, though after a number of experiments I have found ball-bearings of the general type illustrated to be most satisfactory. The left hand face of the fly-wheel 36 and the right hand face of the fly-wheel 37 are recessed or cupped to accommodate parts of the bearings which project into such recesses, the whole affording a compact construction adapted to exclude foreign matter from access to the bearing.

Encircling and fixed to the shell 30 of the rotor, within the chamber 13, there are two flanges 45 and 46 positioned on the rotor 15 at the opposite edges of the chamber 13, said flanges being flared toward each other and conforming to the inclination of the adjacent walls of the chamber 13, with a clearance or space 47 leading to a series of air-inlet openings 49 in said chamber wall. A similar space or clearance 50 between the flange 46 and the adjacent chamber wall leads to similar air-inlet openings 51 in said chamber wall. At the right hand end of 25 the rotor there are flanges 52 and 53, similar to flanges 45 and 46, spaces or clearances 54 and 55, similar to spaces 47 and 50, and air-inlet openings 56 and 57 similar to air-inlet openings 49 and 51. As shown, these 30 flanges overhang certain of the perforations in the rotor and hence when the machine is in operation any liquid discharged through said perforations will strike the inner inclined surface of the flanges and be deflected toward the deeper portions of the two chambers 13 and 14 and flow along such deeper parts of the chamber walls to the outlet or discharge openings 18 and 19. The flanges 35 rotating at high speed with the rotor act as blowers to draw air in through the openings 49, 51, 56 and 57, inward through the spaces 47, 50, 54, 55, and to force such air out of the chambers through the discharge openings 18 and 19, the draft thus created acting to 40 prevent liquid from flowing along the chamber walls to said spaces where it might find access to the bearings or other parts of the machine from which it should be excluded, and to drive to the discharge openings of 45 said chambers liquid and any small solid particles of material expelled through the perforations of the rotor. To insure a supply of liquid in the chamber sufficient to wash from the surface thereof to the discharge openings any solid material escaping through the perforations of the rotor, I provide each chamber with a water-inlet pipe 60 having within its chamber a double spray nozzle 61 for discharging water toward the inner surfaces of the oppositely positioned flanges 45, 46 or 52, 53. The water thus discharged into the chamber does not find its way through the perforations of the rotor, to the material being acted upon but by 65 reason of the whirling draft in the chamber

is thrown forcibly outward against the inner surface of the chamber wall along which it runs to the discharge opening, flushing from the surface any solid particles which may have lodged thereon.

Figs. 4 and 5 illustrate a construction which, except in the particulars about to be described, is substantially the same as that of the previous figures. In this case, the outer shell 70 of the rotor is thickened about 70 its middle to constitute a broad wheel 71 having secured thereon two tires 72, 73, spaced apart, with the driving belt 74 engaging the wheel 71 between said tires. In this case, the rotor is supported by three 80 pairs of idler wheels 75, 76 and 77, the two wheels of each pair being, as illustrated, preferably cast together in the form of a single double wheel. These three double idler wheels are supported, respectively, on 85 axles 78, 79 and 80 with the interposition of ball-bearings between each wheel and its axle. The axles 78 and 79 are supported in brackets on the main frame or base 81, while the axle 80 is supported in upright brackets 90 83, 84 of the covers 85, 86, respectively. These three pairs of wheels constitute two sets of bearings, one set engaging tire 72 and the other set tire 73; furthermore, the two wheels of the pair 77 have flanges 95 engaging over the inner edge of each tire to oppose longitudinal shifting of the rotor. Instead of a single flight conveyer, such as illustrated in the previous figures, there is shown a single flight ribbon conveyer consisting of a spiral band or ribbon 87, supported by radiating arms 88 on the conveyer core 89.

In Figs. 6 and 7, there is shown still another form of construction, which, except in 105 the particulars described, is substantially similar to that illustrated in Figs. 1 to 3. In this case, the perforated rotor is made in two parts 90 and 91, surrounded at their inner contiguous or abutting ends by strengthening sleeves 92, 93, respectively, the inner ends of said sleeves contacting opposite sides of an inwardly projecting rib 94 on a hub 95, the latter fitting about and being rigidly secured to the two sleeves 92, 93. 110 An outwardly projecting rib or flange 96 on the inner end of sleeve 92 engages a groove or recess about the inner surface of the hub 95; and a similar rib or flange 97 on the inner end of the sleeve 93 engages a similar 115 groove about the inner surface of the hub, this interlocking of ribs and grooves assisting in securing the parts rigidly together. At opposite ends of the hub 95, there are two wheels 98, 99, respectively, which are of considerable weight to serve as fly-wheels, to give a gyroscopic action, the advantage of which has heretofore been mentioned. The outer face of each wheel 98, 99 is dished or 120 cupped to form an inner bearing surface 125

100. The rotor is rotatably supported by three pairs of idler wheels positioned equidistant around the rotor. The lower pair, for example, comprises a mushroom-shaped 5 wheel 101 located in the recessed face of the wheel 98 and bearing against the surface 100 of said wheel 98. A similar mushroom-shaped bearing wheel 102 is located in the recessed face of wheel 99 and engages the 10 bearing surface 100 of the latter. Each of these wheels 101, 102 has an axle or spindle 103 rotating in a bearing bushing 104, the latter being supported in a part of the frame of the machine. The other two pairs 15 of bearing wheels are similar to the pair just described and engage the wheels 98, 99 in a similar manner. These three pairs of wheels constitute two sets of bearings, one set engaging wheel 98 and the other set 20 wheel 99. The driving belt 105 for actuating the rotor passes about the hub 95 between the wheels 98 and 99, as illustrated.

Fig. 8 illustrates a form of construction especially designed for acting upon sugar 25 cane mixed in a subdivided state with hot water, for removing from the mixture the water with the sugar of the cane dissolved therein. Except in the particulars mentioned, the construction of this machine is 30 the same as that illustrated in Figs. 1-3. In this case, the conveyer core 106 is made hollow or tubular throughout the greater part of its length, as indicated in dotted lines, and at its left-hand end where it ex- 35 tends through an opening in the wall of the hopper or chute 107, it communicates with a water supply pipe 108, which pipe has a branch 109 leading to the spray-nozzles 110, 111, which latter are similar to the nozzles 40 61, 61 of Fig. 1. 112, 112 are a series of spray-nozzles tapped into the tubular conveyer core 106 in different radial positions lengthwise of the latter and serving to 45 sprinkle a relatively wide swath of water upon the layer or coating of material being acted upon, which is distributed over the interior surface of the rotor by the action of centrifugal force. The sprayers are so relatively positioned as to sprinkle the entire 50 layer or coating of the material, the edge of the spray distributed by one sprayer overlapping or meeting the edge of the spray distributed by the next adjoining sprayer. In acting upon sugar cane, for example, the 55 water distributed by these sprayers is preferably in a heated condition to more readily dissolve the sugar in the cane. Also the sugar cane in a subdivided state is admixed with hot water before being introduced into 60 the machine through the hopper 107. The construction of the spray-nozzle 112 is shown in detail in Figs. 9 and 10. Each nozzle comprises a short tubular part 113 screw-threaded through the wall of the tubular 65 core 106, a convex spreading surface 114

against which the water is delivered from the tubular part 113 and a second convex surface 115 bent at an angle to and forming a continuation of the surface 114 and having a curved perimeter. It has been demonstrated that such a nozzle spreads the water in a wide finely subdivided sheet or spray.

The form of hopper 107, illustrated in Figs. 8 and 12, is especially designed for handling materials such as subdivided sugar cane, which by reason of its fibrous, stringy character tends to clog in bends, angles, or recesses of passages through which it is conveyed. To overcome this tendency at the angle or bend of the hopper 107, where the 70 opening through the latter changes from a vertical to a horizontal direction, and also the tendency of such material to lodge in the hopper in the space directly beneath the core 106, means have been provided for projecting into the outer end of the hopper air-jets adapted to act by impact upon the material and forcibly propel it toward the delivery end of the hopper and into the rotor.

To this end, I provide in the outer end wall of the hopper an annular chamber 116 from which a series of nozzles 117 project into the hopper 107 to deliver therein jets of compressed air along the upper cylindrical surface of the core 106 and along the curved bottom surface of the hopper. An air-supply pipe 118 tapped into the annular chamber 116 supplies the desired quantity of compressed air. The hopper 107 has two hinged sections 119, 120 held together in 80 their closed position by bolt 121 and adapted to be swung open to give ready and convenient access to the interior of the hopper.

In Fig. 11, there is illustrated diagrammatically a series or battery arrangement of three centrifugal separators such as illustrated in Fig. 8. The material to be acted upon, such as sugar cane in a subdivided condition, is introduced through the hopper of the first machine 130, passing from that machine into the second machine 131 and from the latter into the third machine 132. The liquid used in spraying the materials in the machine is delivered to the latter in 90 reverse order, that is to say, the fresh liquid, such as hot water, is supplied through the pipe 133 and sprayed upon the material in the third machine 132 where it is extracted from the material by centrifugal action of the rotor; it is thence pumped through the pipes 134, 135 into the second machine 131, where it is sprayed upon the material in that machine; from the second machine the liquid is pumped through pipes 136, 137 to the first machine 130, where it is sprayed upon the material in that machine.

From the first machine, the liquid passes through a pipe 138 to an apparatus, such as an evaporator for removing the sugar in a solid condition. The advantage of carrying the liquid 100 110 115 120 130

through the machines in this order will be apparent.

What I claim is:

1. In a centrifugal machine for separating liquids from solids, the combination of an inclosing casing; a perforated drum or rotor within said casing rotatable on an approximately horizontal axis; means within said rotor for conveying solid material through the same; two sets of supporting bearings spaced apart and positioned about said rotor at approximately the middle thereof; and driving connections acting upon said rotor at its middle between said sets of bearings.
2. In a centrifugal machine for separating liquids from solids, the combination of a perforated drum or rotor rotatable on an approximately horizontal axis; supporting bearings for said rotor; a fly-wheel about and fixed to said rotor; and driving connections for rotating the rotor in its bearings.
3. In a centrifugal machine for separating liquids from solids, the combination of a perforated drum or rotor rotatable on an approximately horizontal axis; supporting bearings about said rotor at approximately the middle thereof and by which the rotor is entirely supported when rotating; a fly-wheel about and fixed to the rotor; and driving connections for rotating the rotor in its bearings.
4. In a centrifugal machine for separating liquids from solids, the combination of a perforated drum or rotor rotatable on an approximately horizontal axis; two sets of supporting bearings spaced apart and positioned about said rotor at approximately the middle thereof; a fly-wheel about and fixed to the rotor at approximately its middle; and driving means acting upon said rotor at approximately the middle thereof.
5. In a centrifugal machine for separating liquids from solids, the combination of a perforated drum or rotor rotatable on an approximately horizontal axis; two sets of supporting bearings spaced apart and positioned about said rotor at approximately the middle thereof; two fly-wheels also spaced apart and positioned about said rotor at approximately the middle thereof; and driving means acting upon said rotor at its middle between said bearings and between said fly-wheels.
6. In a centrifugal machine for separating liquids from solids, the combination of a perforated drum or rotor rotatable on an approximately horizontal axis; a casing forming a chamber about said rotor, said chamber having an exit or discharge opening; and one or more flanges about and fixed

to the rotor and projecting into said chamber and adapted, in rotating with the rotor, to create a suction or draft in said chamber to the discharge opening thereof.

7. In a centrifugal machine for separating liquids from solids, the combination of a perforated drum or rotor rotatable on an approximately horizontal axis; a casing forming a trough-like chamber around the rotor, said casing having an exit or discharge opening; and two flanges about and fixed to said rotor and projecting into said chamber at opposite edges thereof, said flanges being flared toward each other and adapted, in rotating with the rotor, to create a suction or draft in said chamber to the discharge opening thereof.

8. In a centrifugal machine of the character described, the combination of a perforated drum or rotor rotatable on an approximately horizontal axis; a stationary tubular core extending longitudinally within the rotor; a liquid supply means communicating with said core; and sprayer nozzles spaced along said core within the rotor.

9. In a centrifugal machine of the character described, the combination of a perforated drum or rotor rotatable on an approximately horizontal axis; a hopper for delivering to said rotor material to be acted upon, said hopper having one or more fluid discharge openings in its end wall for discharging into the hopper fluid adapted by impact to impart a propelling force to the material in the hopper; and a fluid supply communicating with said opening or openings.

10. In a centrifugal machine of the character described, the combination of a perforated drum or rotor rotatable on an approximately horizontal axis; a core extending longitudinally within said rotor; a hopper for delivering to said rotor material to be acted upon, said core extending through said hopper and being supported at one end by the end wall of the hopper, and said end wall having therein a fluid chamber with discharge openings positioned about said core for discharging into the hopper fluid adapted to impart a propelling force against material in the hopper; and a fluid supply communicating with said chamber.

In testimony whereof I have signed this specification in the presence of two subscribing witnesses.

BENJAMIN DENVER COPPAGE.
